UNITED STATES PATENT OFFICE.

GEORGE N. RABICKOW, OF DONORA, PENNSYLVANIA.

REFRIGERATOR DISPLAY BOX.

Application filed February 13, 1924. Serial No. 692,454.

This invention relates to a refrigerating box or receptacle intended more particularly for use in butcher shops, or other stores or shops selling perishable goods, the invention having more particular reference to a box of this sort in which the goods or articles may be exposed to view.

The invention has for an object to provide a novel and improved refrigerating box of this sort, a further object relating to the provision of means for varying the effective size of the box.

For further comprehension of the invention, and of the objects and advantages thereof, reference will be had to the following description and accompanying drawing, and to the appended claims in which the various novel features of the invention are more particularly set forth.

15

may be adjusted to a position at the inner ends of the shelves 15 as shown in dotted 70 lines in Fig. 2, in which latter position they are vertically aligned with the leaves 25 when the latter are adjusted to vertical arrangement. To rotate the screw shafts 30 in unison a sprocket chain 33 may be looped 75

20 Fig. 1 of the drawing is a perspective view showing my improved refrigerating box.

Fig. 2 is a longitudinal vertical sectional view thereof, this view being taken on the line 2--2 of Fig. 3.

extended through the end wall of the box as at 30' to receive a suitable turning tool. To swing the leaves 25 from horizontal to 80

25 Fig. 3 is a transverse vertical sectional view taken on the line 3—3 of Fig. 2.

Figure 4 is a view similar to Fig. 2 showing the hinged leaves in vertical position. As here embodied my improved box com- worm gear segments are engaged by the worm pinions 37 on a shaft 38 extending along the rear wall and which is operated 85

30 prises the bottom 10 which may be provided with short legs or feet 11, and from which the side walls 12 and the end walls 13 extend upwardly. Formed in the box, at opposite ends thereof, are the horizontally alined shelves 15 which extend from side to side of the box, the space between these shelves being traversed by a number of rods 16, which in conjunction with the shelves form a horizontal partition and divide the box 35 into a top compartment to receive the meat 40 from the last named of the shafts 30 by means of a chain 39 looped over sprocket wheels on the respective shafts 30 and 38. As will be understood, the various operating elements will be proportioned so that movement of the wall elements 31 across the shelves will result in swinging the leaves 25 through arcs of ninety degrees. The shelves 15, wall elements 31, and leaves 25, may be constructed in any suitable manner to resist the passage of heat. 95

or other material, and a bottom compartment to receive the ice for cooling.

Above the partition thus formed, the front walls of the box are formed of a number of glass panes 18 set in suitable frame pieces, the top of the box being formed in part by like glass panes 19, and in part by the inclined glass doors which are hinged to the rear wall of the box to give access to the top compartment. The end walls of the box, above the shelves 15 may likewise be formed of glass panes 20.

55 In case it is not desired to utilize the full area of the top compartment the latter, and also the bottom compartment for the ice, may be decreased in size. As here shown the

shelves 15 have leaves 25 hinged to their adjacent edges as at 26, these leaves being normally sunk in shallow recesses in the shelves and being of a size and shape to form, when swung to vertical position partitions dividing the top compartment into centre and end sections. Extending longitudinally through the box, below the shelves 15, are several, as here shown four, screw shafts 30 on which are mounted the adjustable wall elements 31 which normally lie against the end walls of the box, but which may be adjusted to a position at the inner ends of the shelves 15 as shown in dotted lines in Fig. 2, in which latter position they are vertically alined with the leaves 25 when the latter are adjusted to vertical arrangement. To rotate the screw shafts 30 in unison a sprocket chain 33 may be looped over sprocket wheels 34 on the individual shafts 30, one of the shafts having its end extended through the end wall of the box as at 30' to receive a suitable turning tool. To swing the leaves 25 from horizontal to vertical positions they have worm gear segments 36 fixed to their hinge pintles, which worm gear segments are engaged by the worm pinions 37 on a shaft 38 extending along the rear wall and which is operated from the last named of the shafts 30 by means of a chain 39 looped over sprocket wheels on the respective shafts 30 and 38. As will be understood, the various operating elements will be proportioned so that movement of the wall elements 31 across the shelves will result in swinging the leaves 25 through arcs of ninety degrees. The shelves 15, wall elements 31, and leaves 25, may be constructed in any suitable manner to resist the passage of heat.

While I have illustrated and described a preferred embodiment of my invention it is to be understood that I do not limit myself to the precise construction herein shown, and that various changes and modifications might be made therein without departing from the spirit and scope of the invention as defined in the appended claims. 100

Having thus described my invention what I claim as new and desire to protect by Letters Patent of the United States is as follows:—

1. A refrigerating box having shelves formed at one end thereof having shallow recesses, leaves normally sunk in the recesses of said shelves and hinged to the adjacent 110

ends of said shelves, adjustable wall elements normally arranged adjacent the ends of the box and adapted for adjustment to positions under the said adjacent edges of 5 said shelves.

2. A refrigerating box having shelves formed at one end thereof having shallow recesses, leaves normally sunk in the recesses of said shelves and hinged to the adjacent 10 ends of said shelves, adjustable wall elements normally arranged adjacent the ends of the box and adapted for adjustment to positions under the said adjacent edges of 15 said shelves, and means for moving said walls and swinging said shelves in unison.

3. In a refrigerating box, a pair of shelves at the ends of the box having shallow recesses, rods connecting adjacent edges of the shelves, leaves normally sunk in the recesses of said shelves and hinged to the said adjacent edges of the shelves, wall elements located normally against the end walls of the box below the said shelves, screw shafts on which said wall elements are rotated, and an operative connection between said screw 25 shafts and said leaves whereby rotation of the shafts swings the said leaves.

In testimony whereof I have affixed my signature.

GEORGE N. RABICKOW.
